MASTER SHIPPING CONTAINER FOR MULTI-UNIT PACKAGES

Robert M. Bennett, Newtown Square, Pa., assignor to
Container Corporation of America, Chicago, Ill., a
corporation of Delaware

Filed Nov. 29, 1963, Ser. No. 327,010
1 Claim. (Cl. 206—65)

This invention relates to packages and particularly to 10 a master shipping container for transporting a plurality of multi-unit packages.

The invention is particularly concerned with the shipping of the so-called "six-pack" type packages, in units of four or more, in a master shipping tray.

As is known to those familiar with the packaging art it is quite common to package cans and/or bottles of beer, soft drinks, and other products in the so-called "multi-pack" type carton which is a tubular, open-ended, paper-board carton containing one or more parallel rows of 20 articles arranged in side-by-side relation.

It is a primary object of this invention to provide, in a master tray for holding a plurality of open-ended carrier cartons, cushioning means for protecting the exposed articles at the open ends of the cartons.

A more specific object of the invention is a provision, in a tray of the type described, of cushioning tabs cut from the marginal portions of the bottom wall and folded upwardly 90° between the tray side walls and the exposed articles at the ends of the cartons positioned within the 30 tray to cushion the articles from damage due to shocks and bumps incurred in normal handling and shipping.

These and other objects of the invention will be apparent from an examination of the following description and drawing, wherein:

FIGURE 1 is a perspective view of a tray embodying features of the invention;

FIGURE 2 is a top plan view of the structure illustrated in FIGURE 1, with the tray shown filled with multi-unit packages;

FIGURE 3 is a fragmentary transverse vertical section taken on line 3—3 of FIGURE 1; and

FIGURE 4 is a top plan view of a paperboard blank from which the tray of the other views may be formed.

It will be understood that, for purposes of clarity, certain elements have been intentionally omitted from certain views where they are believed to be illustrated to better advantage in other views.

Referring now to the drawing for a better understanding of the invention, and particularly to FIGURE 1 it 50 will be seen that the tray embodying features of the invention may be formed from the one piece blank B of of suitable sheet material such as corrugated or solid fibre paperboard, as illustrated in FIGURE 4.

The tray includes a generally rectangular bottom wall 55 10 having opposed pairs of side and end walls 12 and 14 hingedly attached to and upstanding from the side and end edges, respectively, of the bottom wall and interconnected at their ends to form a tubular structure open at the top.

It will be seen that the side walls are preferably formed of a single panel; whereas, the end walls are formed from an outer end wall flap 16 hingedly attached to and upstanding from an end edge of the bottom wall and a pair of inner end wall flaps 18 hingedly attached to and extending inwardly from the ends of the respective side walls to be secured to the outer end wall panel 16 in overlapped relationship.

As best seen in FIGURE 2, the tray is adapted to hold a plurality of packages P arranged in side-by-side 70

2

relationship with the longitudinal axis of the packages extending transversely across the tray, or normal to the longitudinal axis of the tray. Each of the packages P includes a sleeve-type, open-ended, wrap-around paper-board carrier containing at least one row of packaged articles such as bottles or cans A extending lengthwise of the carton.

The essential feature of this invention resides in the means of cushioning the exposed or end articles in each of the packages P. This is accomplished by cutting from the bottom wall 10 of the tray a plurality of longitudinally spaced cushion tabs 20 which are cut from the outer side edges of the bottom wall as at 22 and folded upwardly from the bottom wall 90° so as to lie against the inside surfaces of the side walls 12 of the tray. As best seen in FIGURE 3, the tabs are hinged to the lower edges of the tray side walls along hinge lines 24 and are so positioned as to be in abutting engagement with the outer surfaces of the exposed or end articles in each of the packages.

If desired the bottom wall of the tray may also have cut therefrom a plurality of transversely extending spacer or partition tabs 26 which project upwardly between adjacent packages housed within the tray.

Thus, it will be seen by this simple but ingenious arrangement it is possible to double the cushioning effect for the articles packaged within the tray without utilizing any additional board whatsoever, so that a highly efficient and economical package results from the arrangement of the invention.

I claim:

A master shipping container arrangement for multi-packages comprising, in combination:

(a) a plurality of packages including open end cartons each containing at least one row of vertically disposed cylindrical articles with the end articles of the row having cylindrical side portions exposed;

(b) a master container, formed from a unitary blank of foldable paperboard, for holding said cartons in side-by-side relation, including:

(i) a generally rectangular bottom wall having length and width dimensions substantially equal to the combined length and width dimensions of the packages grouped within the container and supporting the bottoms of the packages thereon;

(ii) opposed pairs of side walls hinged to and upstanding from the side edges of the bottom wall, and hingedly connected to each other at their end edges and disposed closely adjacent the sides of the packages for holding them;

(iii) a plurality of cushioning tabs cut from the bottom wall from portions thereof each generally below a respective end article and hingedly attached to a respective side wall and folded upwardly 90° from the bottom wall to between said side wall and adjacent cylindrical side portions of related end articles for cushioning the end articles within the container.
